Watson & Coleman

ATTORNEY.

UNITED STATES PATENT OFFICE.

ERNEST P. BAKER, OF MANSON, IOWA.

DISPENSING APPARATUS.

1,422,913.

Specification of Letters Patent.

Patented July 18, 1922.

Application filed March 12, 1921. Serial No. 451,924.

To all whom it may concern:

Be it known that I, ERNEST P. BAKER, a citizen of the United States, residing at Manson, in the county of Calhoun and State 5 of Iowa, have invented certain new and useful Improvements in Dispensing Apparatus, of which the following is a specification, reference being had to the accompanying drawings.

10 This invention relates to dispensing apparatus and more particularly to an apparatus for removing from a barrel or similar container the contents thereof.

An important object of the invention is 15 to provide a device of this character which may be employed either as a siphon or as a pump, and in which the pump may be employed for priming the siphon.

A further object of the invention is to 20 provide a device of this character which may be readily attached to and detached from a receptacle.

A still further object of the invention is to 25 provide a device of this character which is extremely simple in construction and operation and which may be cheaply manufactured.

A still further object of the invention is to 30 provide a novel adjusting and supporting device whereby the apparatus may be applied to a barrel or similar receptacle and held in any desired adjusted relation thereto. Other objects and advantages of the 35 invention will become apparent throughout the course of the following description.

In the accompanying drawings wherein for the purpose of illustration is shown a preferred embodiment of my invention and wherein like reference characters designate 40 like parts throughout.

Figure 1 is a side elevation partly in section of a dispensing apparatus constructed in accordance with my invention showing the same in position for use as a siphon;

45 Figure 2 is a similar view showing the apparatus in position for use as a pump;

Figure 3 is a front elevation of one of the gripping jaws employed for supporting the siphon in a barrel;

50 Figure 4 is a brace member employed for holding the siphon in vertical position, and

Figure 5 is a detail sectional view of the lower end of the pump.

Referring now more particularly to the 55 drawings, the numeral 10 indicates an inverted U-shaped conduit, one leg 11 of which

is adapted for insertion in a receptacle through a bung-hole or similar opening.

The leg 12 or exterior leg of the U-conduit 10 communicates at its lower end with a 60 substantially horizontally disposed conduit 13 which is provided at a point spaced from the leg 12 with a stop-cock 14. Intermediate the stop-cock 14 and the leg 12 the conduit 13 has an outlet pipe 15 which communicates 65 with the lower end of a pump cylinder 16, the intake of the pump cylinder being provided with a check valve 17 preventing return flow through the conduit 15 to the horizontal conduit 13. The pump cylinder 70 has disposed therein a ported check valved piston 18, the check valves thereof opening in the same direction as the check valve 17.

The upper end of the pump cylinder 16 is provided with a discharge pipe 19, the upper 75 end of which is preferably open and arranged at a higher level than the base of the U-conduit 10, and this discharge pipe is provided intermediate its ends with discharge nozzle 21, the lower end of which is directed 80 downwardly and overhangs a socket 22 in communication with the interior of the horizontal pipe 13 beyond the stop-cock 14 from the leg 12, and is vertically aligned therewith so that they may combine to receive a removable pipe 23 whereby fluid discharged from the nozzle 21 may be directed downwardly into the pipe 23 to pass out at the discharge nozzle 24 thereof.

The nozzle 21, discharge pipe 19 and leg 90 12 of the U-conduit 10 are rigidly connected together by means of a brace 25 embodying loops 25^a, receiving the conduits and nozzle. The end of this brace is extended upwardly, as at 26, and has pivotally mounted thereon, 95 as at 27, a pump handle 28 to one end of which is connected the piston rod 29 of the pump.

The numeral 30 indicates one of a pair of similar adjusting and supporting members 100 which are preferably formed of wood and tapered from end to end, being substantially circular in cross section when combined, the inner faces of these members are provided with a lining 31 of metal, having formed 105 thereon teeth 32. In the use of the clamping member the sections 30 thereof are inserted in a bung-hole 33 of the barrel and the leg 11 of the U-conduit extended therebetween. When the leg 11 has been inserted to the desired distance the members 30 110 may be forced inwardly, causing them to

wedge against the conduit and the teeth thereof to engage in the conduit holding the same against downward movement into the barrel 34. In order that the apparatus may 5 be fully supported, I secure to the conduit 15 the leg 12 of the U-tube, a brace 35, having loops embracing these portions and provide upon the inner or barrel-receiving end of this brace diverging arms 36 adapted to 10 receive and bear against the side of the barrel so as to prevent movement of the apparatus within the members 30 in such manner as to loosen the same.

In the employment of my device the leg 15 11 of the siphon is inserted into a barrel or similar receptacle a desired distance and held in such position by the adjusting and holding members 30, the arms 36 of the brace 35 engaging the side of the barrel and holding 20 the apparatus in upright position. If it is desired to siphon the contents from the barrel the device is secured in such position that the discharge nozzle 24 is sufficiently elevated from the ground to permit the placing 25 therebeneath of a receptacle such as a bucket. The pump is then operated to draw the contents of the barrel into the cylinder thereof, the overflow pipe having previously been employed to connect the nozzle 21 with 30 the nozzle 24. The pumping is continued until the fluid flows through the nozzle 21 downwardly through the nozzle 24 and the stop-cock 14 is then opened, permitting the flow to take place through the legs 11 and 35 12 of the U-conduit through pipe 13 and nozzle 24.

It will be obvious that with this use of the apparatus it is merely necessary to employ the pump to prime the siphon formed by the U- 40 conduit pipe 13 and discharge nozzle 24 thereof, the nozzle 24 being arranged at a lower level than the lower end of the leg 11. This nozzle is preferably made as short as possible in order that the leg 11 may be lowered 45 to the extreme bottom of the barrel without the nozzle coming into contact with the ground. It will be obvious that when the apparatus is employed with a barrel setting upon the ground the entire contents 50 thereof cannot be siphoned since the nozzle 24 would be in engagement with the ground when the leg 11 has its lower end disposed adjacent the bottom of the barrel. The major portion of the contents of the barrel, however, may be removed by siphon and the leg 11 may then be lowered into the barrel to the 55 bottom thereof and remaining contents of the barrel removed by use of the pump. When using the pump, the removable priming pipe 23 is of course removed and a bucket 60

may be held beneath the nozzle by means of a bail-receiving hoop 36^a formed upon the support 25. If desired, a hose 37 may be connected with the outlet nozzle 21 and the fluid pumped directly into any suitable receptacle. 65

From the foregoing it is believed to be obvious that my dispensing apparatus is particularly well adapted for use by reasons of the fact that the contents of a barrel or 70 similar receptacle may be removed by siphoning if so desired, or may be pumped when this is found desirable. It will furthermore be obvious that the construction 75 of the same as hereinabove set forth is capable of some change in modification without departing from the spirit of my invention, and I accordingly do not limit myself to the specific structure hereinabove set forth except as hereinafter claimed. 80

What I claim is:

1. In a device of the type described, a siphon embodying two legs one of which embodies a discharge nozzle, a pump associated with said leg and embodying a discharge nozzle, and means for directing the fluid from the discharge nozzle of said pump into the discharge nozzle of the siphon. 85

2. In a device of the type described, a siphon embodying two legs one of which embodies a discharge nozzle, a pump associated with said leg and likewise embodying a discharge nozzle, removable means for directing the fluid from the discharge nozzle of said pump into the discharge nozzle of the siphon, and means for cutting off the discharge nozzle of the siphon. 90

3. In a device of the type described, a siphon embodying two legs one of which embodies a discharge nozzle, a pump associated with said leg and likewise embodying a discharge nozzle, removable means for directing the fluid from the discharge nozzle of said pump into the nozzle of the siphon, means for cutting off the discharge nozzle of the siphon, and means for securing the siphon in vertically adjusted positions. 100

4. In a device of the type described, a siphon embodying two legs, a pump communicating at its inlet end with one leg of the siphon and embodying a discharge nozzle, a brace member rigidly connecting the last named leg of the siphon, the pump and the pump nozzle and embodying an upward extension, and an operating lever for said pump pivotally mounted upon said extension. 110

In testimony whereof I hereunto affix my signature.

ERNEST P. BAKER
